UNITED STATES PATENT OFFICE

BENJAMIN E. CROWELL, OF MEDIA, PENNSYLVANIA

FURRED WALL AND CEILING STRUCTURE

Application filed June 20, 1929. Serial No. 372,368.

My invention relates to plaster board ceilings and walls supported from overhead floors or nearby wall structures.

A purpose of my invention is to provide a plaster board ceiling or wall of the character indicated that is easy and inexpensive to erect and that well meets the needs of service.

A further purpose is to lessen the requisite thickness for a final coat of plaster on the 10 room side of an erected plaster board ceiling or wall of the character indicated by using thicker boards and providing supporting structural clip members between the boards that project toward the room only very little 15 beyond the room face of the boards and that effectively support the board edges so that the boards lie uniformly in one plane.

Building regulations frequently specify that finished ceilings or walls of the character indicated shall include a total thickness of plaster not less than three quarters of an 20 inch.

It has been usual practice in the past to 25 make up this required three quarter inch total thickness include a three eighth inch plaster board and a surface coat applied wet to the room side of the plaster board of about another three eighth inch.

I use thicker plaster board and a thinner 30 coat of applied plaster, desirably making the plaster board five eighths inch thick and the finish coat about one eighth inch, and thereby greatly lessen delay incident to the time that must be allowed for the applied 35 plaster to dry out, secure a considerably lighter wall in that the plaster board may be made much lighter than the same thickness of applied plaster, and by greatly lessening the quantity of the applied plaster make it 40 commercially possible to use a much better grade of plaster in the applied coat, the higher price for the better grade of plaster being offset by the smallness of quantity now required for the finishing coat.

A further purpose is to support the boards 45 of a plaster board ceiling or wall of the character indicated by furring strip structural clip members each of which has at spaced 50 points preferably hook connection to a main floor or wall structure and a body along and

between the edges of adjoining boards, stiffening the boards from bending, and seating and permanently alining the adjoining edges.

A further purpose is to longitudinally stagger successive boards in furring strip structural clip members with respect to successive boards in a row of wall boards that are supported by the clips end to end in a plaster board ceiling of the character indicated.

I place rows of structural clip members between the rows of end to end wall board, stiffening the end joints between successive boards by placing the structural clip members across the joints, overlapping both boards at the joint to preferably near the middles of the respective boards.

A further purpose is to fasten the adjoining edges of adjacent wall boards in alinement by noncircular key members intermediate the thickness of the boards. 70

A further purpose is to provide desirable forms of structural clip members.

Further purposes will appear in the specification and in the claims. 75

I have elected to show one main form only of my invention, showing however a few detail modifications and selecting a main form and detail modifications that are practical and efficient in operation and which well illustrate the principles involved. 80

Figure 1 is a horizontal section, looking up, showing ceiling and wall structure embodying a desirable form of my invention, the ceiling boards being partially broken away 85 to disclose the overhead concrete floor and insert members carried by the concrete structure to support the ceiling.

Figure 2 is a detail section taken upon the line 2-2 of Figure 1 to enlarged scale and 90 showing a structural clip member seating and supporting adjoining edges of adjacent boards.

Figure 3 is a top plan view of a key clip for holding the edges of adjacent wall board 95 ends even with one another.

Figure 4 is a sectional detail taken to enlarged scale upon the line 4-4 of Figure 1 and showing a clip connection between the ends of adjacent boards. 100

Figure 5 is a vertical detail section showing one form of clip connection between wall and ceiling boards.

Figure 6 is a vertical detail section showing a furring strip clip member corresponding generally to that shown in Figure 2 except that it is shown between adjacent edges of wall boards, where the clip of Figure 2 is shown seating the edges of ceiling boards.

10 Figure 7 is a detail vertical section showing a structural clip member for seating an edge of a wall or ceiling board to a floor or wall.

15 Figure 8 is a vertical section showing a structural furring strip clip member connecting the top of a wall board to the edge of a ceiling board and presenting a furring strip fastening flange to the main wall.

20 Figure 9 is a view generally similar to Figure 8 and showing one form of a connection between a ceiling board and an adjoining wall board, for use at the end of the ceiling board put up last when erecting the ceiling.

25 Figure 10 is a different form for connecting the ceiling to the wall board from that shown in Figure 9.

Figures 11, 12 and 13 are detail vertical sections through different forms of connection between the ceiling and adjacent wall boards.

30 Figure 14 is a fragmentary plan view showing the key clip of Figure 3 in position of use between adjacent boards.

35 Figure 15 is a section taken upon the line 15—15 on Figure 14 and showing a tool used when inserting the key clip.

Figures 16 and 17 are broken vertical sections to enlarged scale taken upon the lines 40 16—16 and 17—17 respectively of Figure 1.

Figure 18 is an enlarged fragmentary detail elevation showing one form of supporting connection between the main overhead floor and the clip members that seat the opposing edges of adjacent ceiling boards.

Figure 19 is a right end elevation of Figure 18.

50 Figure 20 is a view corresponding to a portion of Figure 18 but showing a different form of connection to the overhead supporting concrete.

Figure 21 is a fragmentary perspective view of the structural clip member shown in 55 sectional elevation in Figure 2.

Figure 22 is a fragmentary perspective of the clip shown in Figure 4.

Figures 23 and 24 are fragmentary perspective views of the clip members shown in Figures 5 and 7 respectively.

Figure 25 is a section of a structural furring strip clip member corresponding generally to that of Figure 6 but showing double thickness of metal where Figure 6 shows 65 single thickness.

Figure 26 is a section upon the line 26—26 of Figure 10.

Figure 27 is a fragmentary plan view of a metal sheet structure used in making the structural clip member of Figures 10 and 26, 70 the sheet being shown flat, the full lines indicating shears and dotted lines the positions of right bends.

Figure 28 is a view corresponding generally to Figure 8 but showing a form of furring strip clip member in which the body of the member is made up of two thicknesses of metal instead of the one thickness shown in Figure 8.

Figure 29 is a fragmentary section through 80 adjacent portions of wall or ceiling boards illustrating one form of supporting connection between the nearby main floor or wall structure and the structural furring strip clip member seating the opposing edges of 85 the adjacent wall or ceiling boards, the view corresponding to a section upon the line 29—29 of Figure 30.

Figure 30 is a section taken upon the line 30—30 of Figure 29.

Like numerals refer to like parts in all figures.

Describing in illustration and not in limitation and referring to the drawings:

The broader features of my invention 95 apply to plaster board ceilings and walls made up of boards of any area dimensions and of any thickness.

Some of the detail features however, find 100 particular application for supporting and erecting the standard short length boards now so usual in walls and ceilings.

These standard short boards are sixteen inches wide and come in full and half lengths of forty-eight and twenty-four inches respectively, and Figures 1, 16 and 17 illustrate the furred walls and ceiling of a room made up of a succession of rows of these standard boards, end to end.

One of the principal features of my invention 110 includes a structural furring strip clip member for seating, supporting and stiffening adjoining boards along their adjoining edges, each furring strip clip member preferably extending along a considerable portion of the length of the supported board and being itself supported from the main floor or wall structure.

I herein call my structural clip member a 120 furring member in that it functions like a furring strip to support wall board or the like at a distance from a main wall structure or main ceiling structure, and further in that like a furring strip one of its important functions is to stiffen the supported board along the length of the board.

Clips of the prior art have not been furring strips in the sense used herein in that they have not longitudinally stiffened the board supported by them, being supported upon 130

stiffening members usually channels or angles across the inner faces of the supported boards, and extending transversely to the lengths of the board.

5 I combine a furring strip that has support from the main wall structure with clip members placing the member between the boards and making them of a length to break joints when the wall or ceiling comprises rows of 10 short boards end to end.

The form of my furring strip clip member may be considerably modified according to individual whim and circumstance and I show a few only of these forms at 40, 40¹, 40², 40³, 15 40⁴, 40⁵, 40⁶ and 40⁷ (Figures 2, 6, 8, 9, 11, 18, 19, 21, 25, 29 and 30).

The different forms are alike in so far that each seats adjacent edges 41 and 41¹ of contiguous boards for a considerable portion of 20 the length of these edges and presents an inwardly directed flange 42 toward a main floor or wall structure which supports the member from movement in direction perpendicular to the supported boards.

25 The supporting connection between the main floor or wall structure is desirably a hook presented by the main structure to suitable perforations 43 in the flange 42, and preferably longitudinally rigid with respect to the main structure, as in Figures 29 and 30, where the main structure is a wall.

If the main structure is an overhead floor the supporting connection from the floor to the furring strip clip members may desirably 35 comprise downwardly directed eye inserts 44 in the floor, and suspension hooks 45 between the eyes and the perforations in the furring strip clip members (Figures 18 and 20). The furring strip clip members, as well as the 40 structural clips that have no supporting connection with the nearby floor or wall, are all preferably one piece members, made by suitably cutting and forming metal sheet material.

45 The forms of furring strip clip member shown at 40 and 40⁶ are alike in sectional contour and are used alike, (Figures 2, 18, 19, 29 and 30) so that any advantage of either with respect to the other will normally be in manufacture.

The form 40 (Figures 2 and 21) is cut and stamped from a single thickness of heavy gauge metal while the form 40⁶ is folded and pressed from lighter gauge metal.

55 The clip member shown in Figures 4 and 22 is used between the adjacent ends of end to end boards to keep the contiguous edges of the boards even as at 46, Figures 1 and 17. While the clip 46 is quite satisfactory with 60 sixteen inch width boards, with wider boards I usually prefer to use the furring strip clip already described between the board in that it greatly stiffens the boards across their ends.

65 In the corner connection between wall and

ceiling boards I preferably use any one of a number of different structural clip members or furring strip clip members according to circumstance, examples of my structural clip members being shown in Figures 5, 10, 12, 13 and 23 and of my furring strip clip members in Figures 8, 9 and 28.

These members are each adapted to seat the adjacent corner edges of the wall and ceiling board, the furring strip members having each a stiffening flange 42 for connection to the main overhead floor structure or main wall structure.

The corner boards overlap as in Figures 5, 8, 13 and 12 or do not overlap as in Figures 9, 10 and 28.

In Figure 5 there is no fastening shown between the corner ceiling boards and the clip member other than the mere seating of the edge of the board in the clip. Where the wall board is already fastened against movement inwardly toward the main wall structure there is normally no need for fastening the ceiling board to the wall board other than the mere seating of the boards in the clip as indicated in Figure 5.

Sometimes it is desirable to use the ceiling board to fasten the wall board from lateral movement and in this event I may use the clip shown in Figure 13, which is similar to clips shown in Figures 5 and 23 except that it is provided with a projecting portion 47 which is perforated and fastened to the upper ceiling board by suitable tacks or nails 48.

The furring strip clip members shown in 40 and 40¹ (Figures 2 and 6) are similar except that the latter strip is provided with a flange portion 49 from the inner edge of the stiffening extension 42.

The latter form of furring strip clip member is well suited for fastening to structural members 50 presented by the main wall as indicated in Figures 16, 17 and 25.

The form of furring strip shown in Figure 11 is adapted to fasten the edge of a ceiling board to the main overhead floor structure or to fasten the top edge of the wall board to the main wall structure.

Suitable perforations 43 are provided for connecting the flange portion 42 of the strip to the main supporting structure, floor or wall.

The clip shown in Figure 10 is used at the last corners under erection, for example where a last board 51 across a ceiling has to connect with a wall board 52 already erected.

Optionaly this clip member may be replaced by the furring strip member 40⁸ shown in Figures 9 and 28, which fastens to the main wall or ceiling structure or to members such as angles 53 carried by the main structure.

The lower flap portions 54 may be left in line with the outside of the wall board and

be bent into place after the ceiling board has been pushed into its final position.

The clip shown in Figure 12 may also be used at either end of ceiling board connection 5 with the wall board.

Assuming that a room has both walls and ceiling of plaster board furred out from main supporting walls and a main overhead floor I may erect all the walls first and then the 10 ceiling, may erect two adjacent walls then the ceiling and then the other adjacent walls or may erect the ceiling first and then the walls, the operation of erection and the selection of furring strip clip members desirably 15 differing somewhat according to which one of the different sequences is followed, and in each case the boards may have any dimensions.

When the walls are all erected before the 20 ceiling and the ceiling boards are put up beginning at one corner of the room in successive widths from wall to wall the ceiling and wall boards preferably overlap along two adjacent walls, while along the other adjacent 25 walls the ceiling boards more conveniently end inside the inner wall faces.

Along the first two adjacent walls I may use the structural corner clip member shown 30 in Figure 5, or that shown in Figure 13 or that shown in Figure 12 or may use any one of the corresponding corner furring strip members, and on the other adjacent walls may use the structural clip members shown in 35 Figure 10 or one of the corresponding furring strip members, such as that shown in Figure 9 or Figure 28, or may use the clip member shown in Figure 12, the bottom flaps 54' being bent up after the wall board has 40 been put in place, and suitable nails or tacks 48 being preferably inserted to tie the ceiling and wall boards together.

If I erect the two adjacent walls and then the ceiling, beginning the successive widths of ceiling board at the corner between the 45 adjacent walls, then the ceiling and wall boards desirably overlap at all of the walls and I may use the structural clip member of Figure 5 or of Figure 13 or of Figure 12 or the corresponding corner furring strip members 50 along all of the walls, working from the ceiling downward when putting up the boards of the other adjacent walls.

The last wall board fastenings are then 55 made at the floor desirably using structural clip members such as that shown at 57 in Figures 7 and 24, either already fastened to place by nails or tacks 58 with the flaps 59 on the room side bent down to pass the bottom edge 60 of the board and then after the board is in place set up to hold it,—or the clip member may be placed loosely over the bottom edge of the board while the board is out at the bottom, and then fastened after the bottom 65 of the board has been pushed to place.

If I erect the ceiling first I may make the

ceiling and wall boards overlap at all walls, using the same corner clip member as before, the ceiling ends of the wall boards in the downwardly directed seats presented by the 70 clips on the edges of the ceiling boards; or I may support the wall edges of the ceiling boards with structural clip members as shown in Figure 11, fastening the wall board to the wall structure without clipping it to the adjacent ceiling board. 75

Advantageous detail features of my invention are directed to a method for erecting the short boards of commerce on ceilings and walls.

In the ceiling shown in Figures 1, 16 and 80 17 the furring strip clip members 40 are desirably of length a very little less than the standard length of the wall boards—for example a little less than forty-eight inches where using the forty-eight inch boards. 85

These clips are suspended at each end by a hooked hanger 45 that is in turn suspended from the supporting eyes 44 inserted during the construction of the ceiling.

Assuming the main overhead floor and the 90 main walls to be concrete and the plaster boards sixteen inches by forty-eight inches, the supporting eyes 44 are preferably placed as inserts in the forms for the concrete ceiling, desirably in parallel lines, spaced in the 95 rows sixteen inch centers and between the rows forty-eight inch centers (Figure 1).

The character of ceiling insert 44 is desirably different according to the kind of form used when making the concrete ceiling. 100

When wooden forms are used the type of eye shown in Figures 18 and 19 is easy to insert but less convenient when the floor or wall forms are iron and I prefer to use an insert such as that shown at 44' Figure 20 105 when iron forms are used for forming the main structure.

Obviously the threaded member 60 screwing into the insert 44', Figure 20, may or may 110 not be a rigid portion of the hook members 45' that engage the furring strip members 40.

The perforations 43 in the flanges 42 of the furring strip that receive the hook ends of the members 45, 45', or 45² (Figures 29 and 30) may desirably be elongated somewhat 115 to allow more easy registry with the hook ends when erecting.

Assuming that the wall boards have already been placed the method of erecting a ceiling is as follows:

I insert hangers 45 in the ceiling eyes 44, one in each of the end eyes, that is in each of the eyes adjacent either wall and two hangers in each of the intermediate eyes.

I then attach the furring strip clip members 40 to the hangers, hooking the bottom hook on hangers through the holes 43 in the ends of the furring strip clip members.

There are now parallel lines of the clip members 40 sixteen inches apart and in po- 130

sition to support the adjacent edges of the end to end boards.

To insert the boards into the clips I begin for example in the left hand corner of the room taking first a one half length board 61 which is usually twenty-four inches long.

The edges of the board adjacent to the walls are slipped into structural angle clip members 62 at the top edges of the wall boards

10 Figure 1, different embodiments of the members 62 being shown in Figures 5, 8 and 13.

The outer edge 63 of the board is then inserted into the seat presented by the furring strip ceiling clip 64, the clip being free to swing. This leaves the furring strip member 64 extending about one half board length beyond the first board.

15 I then place one or more clip members 46 on the outer end of the first board.

20 The clip 65 may or may not have support from the main floor above—as shown it does not have this support, being the clip 46 of Figure 4.

I now begin with full length boards, sixteen inches by forty-eight inches putting up one board after another, and the center of the board in every case coming under the row of eyes 44 in the main floor above and at the end to end separations between the successive furring strip clip members.

25 Each board is pushed into the side clips 66 while still sufficiently forward to clear the flange portions of the clips 46 in the middle of the last board end, and then pushed back to seat in the clip 46 against the last board, the outer swinging clip yielding outwardly sufficient to receive the outer edge of the board.

30 In following this system of erection the last placed board when sliding out the clips to insert the following board is still supported on two full sides and half of a third side thereby averting any danger of the board tipping during the operation.

35 When inserting the last board 67 in the line, which must be cut to measure I omit the clip 46 (Figure 4) at its rearward end and insert several key clips 68, Figures 3, 14 and 15.

40 The last board 67 of each line is cut to a length equal to the distance from the edge of the preceding board to the face of the wall boards.

45 The clip member 69 (which is desirably that of Figure 10 or Figure 9) is then placed on the wall edge of the board 67, the board is then pushed into position as usual, its wall edge being pushed up enough to allow the clip to be fitted over the edge of the wall board.

50 The ceiling boards are preferably suitably fastened from upward movement adjacent the walls, as by small nails 70 holding the corner clip members to the wall boards.

This is to prevent the pushing up of the board while applying the plaster.

In applying this system to metal furred walls the vertical floor to ceiling one and a half inch angles 50 may be retained, as illustrated in Figures 16 and 17, or omitted as in Figures 29 and 30.

In the embodiment of Figures 16 and 17 the furring strip members 71 are intended for a conventional showing for any of the 75 suitable furring strip clip members.

The walls are preferably erected before the ceiling.

I secure the clip 57 (Figure 7) to the floor, insert the lower edge of the board between 80 the flanges, fit the clip 71 to the upper edge of the board, then secure the clip to the vertical angles by suitable wires or wire clips 72.

I make the same use of the clip 46 (Figure 4) as on the ceiling and continue the operation similarly as on the ceiling.

85 The clip members at the vertical corners may desirably correspond to the members 40², 40³ or 40⁷ shown respectively in Figures 8, 9 and 28, the member preferably extending 90 from the floor to a little below the ceiling boards.

95 The key 68 are inserted in recesses 73 cut in the adjacent ends of the boards with which the clips are to be used.

100 The keys are provided with non-circular perforations to fit a non-circular shank 74 of a tool 75 and seated upon the tool are inserted lengthwise of the recesses 73 to the middle of the thickness of the boards.

105 The tool is then given a quarter-turn to the position shown in Figures 14 and 15, the key member cutting into the plaster of the adjacent boards as shown.

110 In view of my invention and disclosure variations and modifications to meet individual whim or particular need will doubtless become evident to others skilled in the art, to obtain all or part of the benefits of my invention without coping the structure shown, and I, therefore, claim all such in so far as they fall within the reasonable spirit and scope of my invention.

115 Having thus described my invention, what I claim as new and desire to secure by Letters Patent is:

120 1. In a plaster board room lining, a row of boards end to end across the lining the first board of the row having a length half the length of the succeeding boards of the row in combination with a row of furring strip clip members along one side of the row of boards end to end and seating the edges of the boards, staggered with respect to the boards so that each clip member seats portions of two boards each portion being approximately one half board length.

125 2. In a plaster board room lining, a row of boards end to end across the lining in combination with a row of furring strip clip 130

members along one side of the row of boards end to end and seating the edges of the boards, staggered with respect to the boards the end furring members supporting substantially the 5 whole length of the end boards and a considerable portion of the lengths of the adjacent boards.

3. In a plaster board room lining, a row of boards end to end across the lining in combination 10 with a row of furring strip clip members along one side of the row of boards end to end and seating the edges of the boards, staggered with respect to the boards the end furring members supporting substantially the 15 whole length of the end boards and a considerable portion of the lengths of the adjacent boards, structural clip members intermediate the end members each supporting a considerable portion of the lengths of two 20 adjacent boards.

4. In a room lining, a one-piece furring strip, a main building structure spaced from the strip, a supporting connection between the main structure and strip at points spaced 25 along the strip, and adjoining and relatively perpendicular composition boards having overlapping adjoining edges supported by the strip, the strip including flaps bent at right angles to the plane of the strip at intervals along one edge thereof, other flaps spaced from and parallel to the first flaps bent at right angles in opposite directions from an intermediate portion of the width of the strip and the said other flaps that extend 30 in opposite directions from the first flaps having right angle bends toward the plane of the first flaps, the board thus seating between the flaps seating overlapping corner edges of boards upon opposite sides 35 of the strip, and presenting a strip portion toward the main wall.

5. In a room lining, a one piece furring strip relatively perpendicular wall boards presenting adjacent corner edges to the strip having flaps spaced along the strip bent outwardly at right angles from the strip in opposite directions along a line spaced somewhat inwardly from one edge of the strip, the flaps on one side of the strip having a forward right angle bend so as to extend parallel to the strip toward the said edge there and other right angle bend flaps spaced inwardly from the first flaps on the other side of the strip, the furring strip thereby seating 50 adjacent corner edges of the relatively perpendicular adjoining boards with the inner corners adjoining.

6. In a room lining, a structural clip member for seating overlapping edges of adjoining corner composition boards and including a strip having spaced along the strip flap bends to seat the edge of one of the boards that overlaps the other and having bends on one of the flaps downwardly adapting the said lateral downward portions in

cooperation with the lower edge of the strip to seat the edge of the other board.

7. In a room lining, a connection between adjacent plaster board for holding the edges of the boards even and including a flat key having a length greater than its width and adapted to be inserted to position between the inner and outer edges of the boards in a suitable cut or recess between the boards and to be turned in its own plane 90° to key 70 the boards together.

8. In a room lining, a structural member including a generally oblong strip having near its central portion a non-circular keyhole and being adapted to be placed between adjacent 80 boards intermediate the thickness thereof and then to be given a right angle turn in its own plane by engagement at the keyhole to cut into the adjacent boards and thereby to hold the edges of the boards even.
